UNITED STATES PATENT OFFICE.

CLAUDE A. MALLORY, OF MADISON, SOUTH DAKOTA.

REFLECTOR.

Application filed June 7, 1922. Serial No. 566,454.

To all whom it may concern:

Be it known that I, CLAUDE A. MALLORY, a citizen of the United States, residing at Madison, in the county of Lake and State 5 of South Dakota, have invented new and useful Improvements in Reflectors, of which the following is a specification.

This invention relates to improvements in reflectors, the general object of the invention 10 being to provide means for reflecting the rays of light upon an object, the invention being more especially designed for use in photography.

Another object of the invention is to provide a frame with a plurality of reflectors 15 therein, each reflector being formed of a single piece of material which supports the mirrors.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is a side view of the invention. Figure 2 is a front view thereof.

Figure 3 is a front view of the reflectors.

Figure 4 is a section on line 4—4 of Figure 3.

Figure 5 is a section on line 5—5 of Figure 3.

Figure 6 is a view of the blank from which the mirror support of the reflector is formed.

Figure 7 is a detail view of the means for holding the lamp socket.

In these views 1 indicates a wheeled base which supports the uprights 2. A bar 3 is slidably mounted on each upright and this 45 bar has a rack 4 thereon which is engaged by a toothed wheel 5 on a shaft 6 which is mounted in brackets 7 secured to the uprights. This shaft is provided with a handle 8 and with ratchet mechanism 9 for holding it in adjusted position. By this means the rods 3 may be raised or lowered as desired.

A reflector frame 10 is pivotally secured to the upper ends of the rods 3, the frame being held in adjusted position by the nuts 11.

55 A diffusion screen 12 is supported by the arms 13 which are pivotally secured to the

screen and these arms are adjustably secured to the uprights 3 by the set screws 14, the arms passing through holes formed in parts on the rods and set screws pass 60 through these parts and engage the arms. A reflecting screen 15 is adjustably secured to the frame 10, as shown at 16, and a screen 17 is adjustably connected with the top of the frame 10, as shown at 18. These screens 65 15 and 17 may be composed in part of white cloth or metal and act to reflect the rays of light from the reflector 10.

The reflector frame carries a number of reflectors 19, each of which is provided with 70 a lamp 20. Each reflector has its base formed of a single piece of material cut and bent as shown in Figures 4, 5 and 6. This piece 19' is cut, as shown at 21, and the small strip 22 is lapped over the opposite edge 75 of the cut part. The blank is bent on the converging lines 23 so that when the strip 22 is secured to the adjacent part the blank will assume a flat pyramidal form. The corners of the blank are cut away, as shown 80 at 24, and the edges of the blank are bent to form the main flanges 25 and the small flanges 26, these small flanges 26 being located in the corners. Four triangular mirror strips 27 are placed in each reflector, 85 the strip being held in by bending the flanges 26 over the corners, the extremities of said flanges 26 being bent down to engage the edges of the strips. The pointed ends of the mirror strips are held in place by a flexible washer 28 and the bolt 29 which passes through the center of the base. Some of the flanges 25 are secured to the frame 10 while others are bent and fastened together, as shown at 30. The cut away corners of the blanks leave openings 31 which provide ventilating openings for the device 90 and also permit the conductor wires to the lamps 20 to pass through. The lamp sockets 32 are carried by the threaded members 33 which are adjustably mounted on the brackets 34, connected with the frame 10, by the nuts 35. Thus the lamps may be adjusted 95 relative to the reflectors.

Figures 1 and 2 simply show one way 100 of using the reflector frame as it will be understood that this frame can be used in a number of different ways. The improved reflector frame will permit a small bulb to be used and the light will be thrown over a 110 broad area. Pictures can be made with my reflector with far less electric current than

with ordinary reflectors. The fact that the light comes from several points broadens the effect and makes the shadows less sharp. By getting the volume of light without taking it all from one little spot gets away from a large amount of glare always present where a large amount of light comes from a very small spot. This is decidedly noticeable in using a row of these reflectors. There is absolutely no strain on the eyes or glare of any kind and while there is a good working light there is less glare than if stronger bulbs were used that really give less to work by. It represents a more truly daylight effect both to the eyes of those working with it and in the finished picture as well. It can be reflected on the shadow side of the picture the same as though it were light from a skylight. Pictures made with a row of these reflectors show a longer scale of shadow tone than ordinary electric results.

I desire it to be understood that I may make changes in the construction and in the combination and arrangement of the several parts, provided that such changes fall within the scope of the appended claims.

What I claim is:—

1. A device of the class described comprising a frame, a plurality of reflectors in the frame, each reflector consisting of a base formed of a single piece of material formed into a flat pyramid, mirror strips resting against the inner sides of the pyramid, flanges on the base bent over the mirror strips to hold them in place, flanges on the base adapted to be secured to the frame and

to flanges of other bases and an electric lamp associated with each reflector.

2. A device of the class described comprising a frame, a plurality of reflectors in the frame, each reflector consisting of a base formed of a single piece of material formed into a flat pyramid, mirror strips resting against the inner sides of the pyramid, flanges on the base bent over the mirror strips to hold them in place, flanges on the base adapted to be secured to the frame and to flanges of other bases, an electric lamp associated with each reflector, and means for adjusting the lamp transversely in relation to the center of the reflector.

3. A reflector of the class described comprising a frame, a plurality of reflectors placed in the frame, each reflector comprising a base of pyramid shape and mirror strips placed upon the inner faces of the pyramid base, flanges upon the base for engaging the strips, a bolt passing through the apex of each base and a flexible washer on each bolt for engaging the pointed ends of the mirror strips.

4. A device of the class described comprising a reflector frame, a plurality of reflectors therein, a lamp associated with each reflector, an adjustable support for the reflector frame, screens adjustably connected with the reflector frame arm slidably connected with the frame and a screen carried by said arms in front of the frame.

In testimony whereof I affix my signature.

CLAUDE A. MALLORY.
